UNITED STATES PATENT OFFICE.

BENNIE T. GRINDELAND, OF MABEL, MINNESOTA.

SHOE-BUCKLE.

1,311,120.

Specification of Letters Patent. Patented July 22, 1919.

Application filed November 23, 1917. Serial No. 203,557.

To all whom it may concern:

Be it known that I, BENNIE T. GRINDELAND, a citizen of the United States, residing at Mabel, in the county of Fillmore and 5 State of Minnesota, have invented certain new and useful Improvements in Shoe-Buckles; and I do hereby declare the following to be a full, clear, and exact description of the invention, such as will enable others 10 skilled in the art to which it appertains to make and use the same.

This invention relates to buckles, and more particularly to buckles especially adapted for shoes and the like, and the primary object of 15 the invention is to provide a buckle for shoe closures which will be simple and easy to operate, so that the shoe can be readily removed from and placed on the foot.

A further object of the invention is to 20 provide an improved means for attaching the buckle to one edge of the shoe closure, so that the buckle cannot be torn from the shoe upper.

Another object of the invention is to 25 provide an improved shoe buckle including a base plate carrying a pivoted clamp member having formed thereon a plurality of teeth for biting into the connecting member, and a reinforcing plate adapted to engage the un- 30 der surface of the shoe upper and having a pair of spaced integrally formed rivets, which are adapted to be inserted through the shoe upper and engage the base plate, so that the shoe upper will be securely clamped be- 35 tween the reinforcing plate and the base plate.

A still further object of the invention is to 40 provide an improved buckle of the above character, which is durable and efficient in use, one that is simple and easy to manufacture, and one that can be placed upon the market at a reasonable cost.

With these and other objects in view, the 45 invention consists in the novel construction, arrangement and formation of parts, as will be hereinafter more specifically described, claimed and illustrated in the accompanying drawing forming a part thereof, in which:

Figure 1 is a fragmentary front elevation 50 of a shoe upper provided with the improved buckle,

Fig. 2 is a longitudinal sectional view through the improved buckle,

Fig. 3 is a perspective view of the buckle, 55 and

Fig. 4 is a detail perspective view of the re-

inforcing plate, showing the rivets formed integrally therewith.

Referring to the drawing in detail, where- 60 in similar reference numerals designate cor- responding parts throughout the several views, the numeral 1 generally indicates the improved buckle, which is adapted to be connected to a shoe or overshoe closure or upper 2. Each shoe closure is preferably provided 65 with three or more of the improved buckles, so that the upper will be held tightly around the foot of the user at all points. The buckles 1 are adapted to be secured adjacent one edge of the meeting edges of the shoe clo- 70 sure 2, while the flexible straps 3 are adapted to be secured to the adjacent edge, and these flexible straps form means for engaging the buckles. Suitable fastening elements 4 are provided for holding the flexible straps 3 in 75 position. The improved buckle 1 includes a substantially flat base plate 5, having its side edges bent upwardly, as at 6, to provide ears 7, which are provided with registering aper- 80 tures 8, which rotatably receive trunnions 9 formed on the opposite side edges of the plate 10. The ears 7 are beveled rearwardly, as at 11, so that the plate 10 can be readily gripped. The trunnions 9 are formed inte- 85 grally with the plate 10, and are formed by cutting the side edges of the plate trans- versely and then rolling the cut portions to- 90 ward the front edge of the plate, where the metal is uncut. The forward edge of the plate 10 is bent downwardly at right angles and cut to provide a plurality of biting teeth 12, the purpose of which will hereinafter 95 fully appear.

A flat rectangular reinforcing plate 13 is provided for attaching the buckle to the 95 shoe upper, and this plate is positioned on the inner surface of the shoe closure directly beneath the base plate 5. The reinforcing plate 13 is provided with integral rivets 14 on its side edges, and these rivets are formed 100 by cutting the side edges of the plate in- wardly toward the central portion of the plate, and then bending the cut portion up- wardly, as at 15, and rolling the ends of the cut portions toward each other until the 105 rivets are formed. The base plate 5 is pro- vided with a pair of spaced apertures 16, and the rivets are forced through the shoe upper and through said openings, and the same are then upset, as at 17. This forma- 110 tion firmly secures the buckle in position and clamps a relatively large portion of the shoe

upper to the buckle, so that tearing of the buckle from the shoe upper is reduced to a minimum.

In operation of the improved device the 5 buckles are secured to the upper in the above-described manner, and the plate 10 is moved upwardly at right angles to the base plate, so as to position the tongues 12 parallel therewith, and the straps 3 are then inserted 10 between the ears 7, and when the same are positioned at the desired point the plate 10 is thrown downwardly, which will forcibly bring the teeth 12 into engagement with the flexible strap, and thus prevent removal 15 thereof. The rear end of the plates 10 engages the upper surface of the base plate 5 when the same is in its operative position, and a pull on the straps 3 will tend to throw the tongues 12 outwardly, and thus bring the 20 rear edge of the plate 10 forcibly into engagement with the base plate, which will prevent any further movement of the tongues.

The base plate 5 is provided with a slot 25 18, which is positioned adjacent to and parallel with the front edge of the base plate, and this slot is adapted to receive a portion of the flexible strap 3, when the tongues 12 are forced into engagement with the same. 30 The tongues depress the straps and force a slight portion of the same into the slot, which will effectively hold the strap against movement. This slot 18 can also be utilized as a guide opening, when a relatively small 35 strap is used, and in this instance the small strap is inserted through the slot 18 and thence brought over the top 17 of the base plate 5, and the plate 10 is then operated to forcibly bring the teeth 12 into engagement 40 therewith.

Copies of this patent may be obtained for five cents each, by addressing the "Commissioner of Patents, Washington, D. C."

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be 45 resorted to, when required, without sacrificing any of the advantages of my invention as set forth.

What I claim as new is:

In a buckle of the class described, a flat 55 base plate, upstanding ears carried by the base plate, a plate pivotally supported by said ears, a plurality of downturned teeth formed on the forward edge of said pivoted plate, said base plate adapted to be positioned on the outer surface of the article which is to be secured, rivets adapted to be forced through an article and secured to said base plate for securing said buckle thereto and forming a rest for a strap arranged to be engaged by the buckle to space the same from the base plate, thereby permitting the tongues to readily bite into the strap, and a flat reinforcing plate positioned on the inner surface of the article directly 60 65 below said base plate and connecting said rivets to prevent displacement thereof, as and for the purpose specified.

In testimony whereof I affix my signature in presence of two witnesses.

BENNIE T. GRINDELAND.
